(57) **CLAIM**

We claim the ornamental design for a surgical nail, as shown and described.

DESCRIPTION

FIG. 1 is a front view of a design for a surgical nail; FIG. 2 is a front perspective view thereof;

FIG. 3 is an enlarged front view of Area A of FIG. 1 of the bottom end thereof;

FIG. 4 is an enlarged side view of Area B of FIG. 2 of the bottom end thereof; and,

FIG. 5 is an enlarged bottom perspective view on an opposite side of Area A of FIG. 1 of the bottom end thereof. The dot-dash broken lines dash-dot lines indicate where enlarged portions are taken from and form no part of the claimed design.

1 Claim, 5 Drawing Sheets
